Primary Examiner—Alan P. Douglas*Assistant Examiner*—Lavone Tabor*Attorney, Agent, or Firm*—Vidas, Arrett & Steinkraus, P.A.**[57] CLAIM**

The ornamental design for a manicure brush, as shown and described.

DESCRIPTION

FIG. 1 is a front view of a manicure brush showing my new design with the rear and right and left sides being identical thereto;

FIG. 2 is a top plan view thereof;

FIG. 3 is a bottom plan view thereof;

FIG. 4 is a perspective view thereof;

FIG. 5 is a bottom perspective view thereof, shown with the brush capped to a container; and,

FIG. 6 is an exploded top perspective of FIG. 5 shown with a portion of the handle covered.

The broken lines that are shown in FIGS. 1, 3, 4, 5, and 6 are for illustrative purposes only and form no part of the claimed design.

1 Claim, 2 Drawing Sheets*Fig. 1**Fig. 2**Fig. 4**Fig. 3**Fig. 6*
